Atty's.

UNITED STATES PATENT OFFICE.

BERT CARLISLE, OF SANTA ANA, CALIFORNIA.

SPACING DEVICE FOR WRAPPING-PAPER ROLLS.

1,301,037.

Specification of Letters Patent. Patented Apr. 15, 1919.

Application filed February 6, 1918. Serial No. 215,664.

To all whom it may concern:

Be it known that I, BERT CARLISLE, a citizen of the United States, residing at Santa Ana, in the county of Orange and State of California, have invented new and useful Improvements in Spacing Devices for Wrapping-Paper Rolls, of which the following is a specification.

My object is to make a roll paper cutter having a spacing device parallel with the cutting edge of the paper cutter and adapted to engage under the paper and guide it outwardly from the roll so that it may be easily grasped and torn off, and my invention consists in the novel features herein shown, described and claimed.

Figure 1 is a perspective of a paper cutter provided with a spacing device in accordance with the principles of my invention.

Fig. 2 is a perspective of the cutter bar and spacing device removed from the supporting arms.

Fig. 3 is an enlarged cross-sectional detail on the line 3—3 of Fig. 1 and illustrating the operation.

The roll paper cutter 1 comprises standards 2 and 3, a top 4 connecting the upper ends of the standards, horizontally aligned bearings 5 in the standards to support the spindle 6 upon which the roll paper 7 is mounted, and spring-pressed arms 8 connected to the top 4 and projecting forwardly. The parts 2—8 are or may be of the ordinary

construction.

In the construction shown in Figs. 1, 2 and 3, I apply the cutter bar 9 to the outer ends of the spring-pressed arms 8 and attach the spacing bar 10 to the cutter bar.

The details of the cutter bar 9 are as follows: The cutter bar is preferably formed of sheet metal. A piece of metal is cut substantially rectangular and the sheet of metal is bent longitudinally on the line 11 to form the flat straight blade 12 having the straight cutting edge 13 at its forward side and the attaching bar 14 extending upwardly and backwardly from the line 11 and having sockets 15 and 16 to receive the spring-pressed arms 8. The socket 15 is formed by cutting longitudinal parallel slits 17, 18 and 19 in the metal and bending the portion 20 between the slits 17 and 18 backwardly and the portions 21 and 22 forwardly, the portion 21 being between the slits 18 and 19 and the portion 22 being above the slit 17. The

arm 8 has a recess 23 formed from its back side to fit the portion 20 and the arm is inserted downwardly back of the portions 21 and 22 and in front of the portion 20, and the portion 20 hammered into the recess 23. The other arm 8 is connected to the socket 16 in a similar manner, so as to rigidly connect the cutting edge to the spring-pressed supporting arms and so as to hold the cutting edge 13 outwardly from the roll paper 7.

The spacing bar 10 is cut and pressed from sheet metal and comprises the guide plate 24 fitting below the plate 12 and having a notch 25 in its front face, the spacing bar 26 bent upwardly from the back side of the plate 24, and the flanges 27 bent upwardly and forwardly from the ends of the plate 24 and the ends of the spacing bar 26 to fit against the lower faces of the ends of the plate 12 and the back faces of the ends of the attaching bar 14, the parts being rigidly secured together along the lines 28 by brazing, welding, soldering or the like. The upper rear edge 29 of the spacing bar 26 is adapted to bear directly upon the face of the roll 7 so that the edge 30 of the paper will pass over the edge 29 and downwardly in front of the bar 26 behind the bar 14 and then forwardly upon the plate 24 under the plate 12.

When the paper is torn off along the edge 13, the uncut piece will lay upon the plate 24 with the edge 30 at the edge 13 and when another piece of paper is desired the operator may pass his fingers under the paper through the notch 25 and pull the paper forwardly to the desired extent. In this way the edge of the uncut paper is always spaced away from the roll in position convenient to the operator instead of clinging to the roll, as in the old cutters. The back bar 26 rides upon the face of the roll, the spacing flanges 27 hold the attaching bar 14 outwardly from the roll and the plate 24 guides the free edge of the paper outwardly from the roll.

Various changes may be made in the details of construction without departing from the spirit of my invention as claimed.

I claim:

A spacing device for roll paper cutters, comprising the combination with a paper cutter construction having spring-pressed arms, of a piece of flat metal bent longitudinally to form a flat straight blade and an

attaching bar, means for connecting the attaching bar to the ends of the spring-pressed arms, and a spacing bar mounted behind the blade and bar to bear against a paper roll 5 and guide the paper between the blade and spacing bar; said spacing bar construction comprising a piece of sheet metal cut and bent to form a guide plate, a spacing bar, and flanges extending upwardly and for-

wardly from the ends of the guide plate and 10 the ends of the spacing bar and fitting against the lower faces of the ends of the blade and the back faces of the ends of the attaching bar; the parts being rigidly secured together. 15

In testimony whereof I have signed my name to this specification.

BERT CARLISLE.
